UNITED STATES PATENT OFFICE.

HENRY E. SHAFFER, OF ROCHESTER, NEW YORK.

DESIGN FOR AN ACETYLENE-GAS BURNER.

SPECIFICATION forming part of Design No. 31,030, dated June 20, 1899.

Application filed May 8, 1899. Serial No. 716,031. Term of patent 7 years.

To all whom it may concern:

Be it known that I, HENRY E. SHAFFER, a citizen of the United States, residing at Rochester, New York, have invented and produced 5 a new and original Design for Acetylene-Gas Burners, of which the following is a specification, reference being had to the accompanying drawings, forming a part thereof.

Figures 1 and 2 are elevations, taken at right 10 angles to each other, of a gas-burner employing my new design.

As shown in the drawings, the leading or material feature of my design consists in the 15 diverging arms A, arising from a central vertical stem, and having projections extending

inward from the upper part of each arm. The vertical stem is circular and arranged at its upper end to receive the lower ends of the divergent arms. The arms are square, with flat sides, and the stem has projections of corresponding shape where it meets the arms. 20

Having described my invention, what I claim as new, and desire to secure by Letters Patent, is—

The design for an acetylene-gas burner, as 25 herein shown and described.

HENRY E. SHAFFER.
